UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPE-BAR.

No. 858,756.

Specification of Letters Patent.

Patented July 2, 1907.

Application filed October 23, 1901. Renewed November 12, 1904. Serial No. 232,528.

To all whom it may concern:

Be it known that I, FRANCIS H. RICHARDS, a citizen of the United States, residing at Hartford, in the county of Hartford and State of Connecticut, have invented 5 certain new and useful Improvements in Type-Bars, of which the following is a specification.

This invention relates to typebars and typebar-blanks, and has for an object to furnish a typebar (linotype) the body portion of which is of such form 10 and structure as shall afford especial facilities for removing dirt or foreign matter that may collect on the faces thereof, thus enabling a number of bars to be closely assembled, or piled up fairly and solidly.

This result I accomplish by providing a number of 15 grooves or depressions in either one or both of the side faces of the bar, which grooves are relatively narrow as compared with the portions of the face of the bar between them and which contact with the side face of an assembled and contiguous bar. Upon rubbing adjacent bars together these faces will slide one upon the other and any particles of dirt or like matter adhering to the side of the bar will gradually be worked off into the narrow grooves, thus permitting the bars to lie together in close contact.

25 In the drawing accompanying the present specification, Figure 1 is a side elevation of a typebar embodying my present improvements, the grooves or channels being formed only on one side face thereof and part of the bar depthwise thereof being broken away. 30 Fig. 2 shows the opposite side of the bar, which in the particular form and structure of bar shown, is unprovided with grooves. Fig. 3 is a perspective view of that portion of a typebar below the printing portion thereof, the same being provided upon one of its faces 35 with relatively narrow grooves or channels, as in Figs. 1 and 2. Fig. 4 is a cross-sectional view through a pair of assembled typebars or typebar-blanks, such as set forth in Figs. 1 to 3 inclusive, showing the relation which the grooves may bear to each other. Fig. 5 is a 40 view similar to Fig. 4, illustrating that construction of a typebar or typebar-blank in which each side face thereof is provided with a relatively narrow groove, the groove on one face being disposed between adjacent grooves on the opposite face.

45 Similar characters of reference designate corresponding parts in all figures.

This invention may be said, in general to involve a construction for the body portion of a typebar in which grooves or channels are made in either one or in both 50 of those faces of the bar which contact with a contiguous face or faces of other bars when assembled therewith. This body portion may constitute an integral part of the typebar, or it may form one component of

a composite bar. It may also constitute the body portion of a blank from which a typebar is to be made. 55

Referring to Figs. 1, 2, and 3, B designates a typebar, which in this instance is a one-piece bar, although the present invention is not limited in its application to typebars of any particular character or nature, as they may be of integral or composite form and of a cast 60 metal or of a relatively ductile metal upon whose edge the types are formed directly by some suitable process, such for instance, as one capable of producing wrought types. The various types are designated without preference by t.

The grooves 2 in the side face of the bar preferably 65 extend at an angle to the horizontal axis or line of length thereof, the angular relation being, in the illustrated relation, a substantially right-angled one. These grooves 2 preferably extend from top to bottom of the 70 bar and are relatively narrow, as clearly illustrated, thus leaving comparatively large areas between them with which the adjacent bar contacts when the bars are assembled.

A typebar having grooves or channels of this relatively narrow width and comparative great separation one from the other is distinctly different from constructions in which either one or both of the side faces of the bar is provided with projections located at comparatively great distances apart, which projections contact with the contiguous bar when the bars are assembled. In this latter case the area of contact is comparatively small and the bar or body portion is extremely liable to bend between the two adjacent lines of contact along the projecting portions. This objection, 80 however, is not present in the bars constructed according to the present invention, since, as before stated, the grooves being comparatively narrow do not give rise to an absence of contact over an unduly wide distance measured lengthwise of the bar. When two bars 85 so constructed are rubbed together, therefore, while in contact, dirt or foreign matter on the faces of the bars is readily and rapidly worked into the grooves 2, thus enabling the bars to be pressed into close contact.

Although in Figs. 1, 2, 3, and 4 these grooves 2 are 95 shown only in one side face of the bar, evidently they may also be made upon both faces thereof. This construction is set forth in Fig. 4, in which the grooves 2 upon the two faces are not, however, as shown, disposed directly opposite each other, but are staggered, that is, 100 the grooves upon one face are located between the grooves upon the opposite face.

In using the term "typebar" it will be understood that the term "typebar-blank" is also included.

Having described my invention, I claim— 105
1. A typebar provided with dirt-collecting grooves or

- depressions of comparatively narrow width in its side face.
2. A typebar provided with dirt-collecting grooves or depressions of comparatively narrow width in its side face, which grooves or depressions are disposed at an angle to the line of length of the blank. 5
3. A typebar provided with dirt-collecting grooves or depressions of comparatively narrow width in its side face, said grooves or depressions extending substantially in line with the vertical height of the blank. 10
4. A typebar provided with dirt-collecting grooves or depressions in its side face, the width of which grooves or depressions is less than the width of the surfaces between adjacent grooves or depressions, and which contact with an adjacent bar when the bars are assembled. 15
5. A typebar provided with dirt-collecting grooves or depressions in its side face, the width of which grooves or depressions is less than the width of the surfaces between adjacent grooves or depressions, and which contact with an adjacent bar when the bars are assembled, and said grooves or depressions extending substantially in line with the height of the bar. 20
6. A typebar having dirt-collecting grooves or depressions of comparatively narrow width in both of its side faces. 25
7. A typebar having dirt-collecting grooves or depressions of comparatively narrow width in both of its side faces, said grooves or depressions on one face being located between the grooves or depressions on the opposite face. 30
8. A typebar having dirt-collecting grooves or depressions of comparatively narrow width in both of its side faces, said grooves or depressions on one face being located between the grooves or depressions on the opposite face, and all of said grooves or depressions extending substantially in line with the vertical height of the bar. 35
9. A typebar having dirt-collecting grooves or depressions of comparatively narrow width in both of its side faces, said grooves or depressions on one face being located
- between the grooves or depressions on the opposite face, and all of said grooves or depressions extending substantially in line with the vertical height of the bar, and said grooves or depressions each being of a width less than the portion of the side face of the blank intervening between adjacent grooves. 40
10. A typebar having dirt-collecting recesses of comparative narrow width at a comparatively wide distance apart in its side face. 45
11. A typebar having dirt-collecting recesses of comparative narrow width at comparative wide distances apart in both of its side faces. 50
12. A typebar having dirt collecting grooves of comparative narrow width at comparatively wide distances apart in each of its side faces, and the recesses at one side being opposite the face on the other side, whereby when several of these are assembled, the recesses of one will scavenge the faces of those juxtaposed. 55
13. A typebar having dirt collecting recesses in its sides of comparatively narrow width and the recesses on opposite sides being differently disposed whereby when several of these are assembled the grooves of one will scavenge the others. 60
14. A typebar provided with scavenger grooves of comparatively narrow width in its side face, the juncture of the walls of the groove with the walls of the face forming a sharp angle forming scrapers. 65
15. A typebar having in each of its side faces a number of comparatively narrow scavenger grooves, and the grooves in the opposite side faces being located at different relative positions whereby when several of these are assembled the grooves on contacting side faces will be out of register. 70
